(57) **CLAIM**

The ornamental design for a pour-over kettle, as shown and described.

DESCRIPTION

FIG. 1 shows a perspective view of a pour-over kettle showing my new design, according to an embodiment of the invention.

FIG. 2 shows a perspective view of a pour-over kettle showing my new design, according to a second embodiment of the invention.

FIG. 3 shows a perspective view of a pour-over kettle showing my new design, according to a third embodiment of the invention.

FIG. 4 shows a perspective view of the kettle portion of the pour-over kettle shown in FIGS. 1, 2 and 3, shown separately for ease of illustration.

FIG. 5 shows a front, elevation view of the kettle portion shown in FIG. 4, shown separately for ease of illustration.

FIG. 6 shows a rear, elevation view of the kettle portion shown in FIG. 4, shown separately for ease of illustration.

FIG. 7 shows a left, elevation view of the kettle portion shown in FIG. 4, shown separately for ease of illustration.

FIG. 8 shows a right, elevation view of the kettle portion shown in FIG. 4, shown separately for ease of illustration.

FIG. 9 shows a top, plan view of the kettle portion shown in FIG. 4, shown separately for ease of illustration; and,

FIG. 10 shows a bottom, plan view of the kettle portion shown in FIG. 4, shown separately for ease of illustration. The broken lines in FIG. 3 show portions of the pour-over kettle that form no part of the claimed design.

1 Claim, 9 Drawing Sheets
